UNITED STATES PATENT OFFICE.

VAUGHAN L. ANDREW, OF SUPERIOR, WISCONSIN.

WINDMILL.

Application filed August 8, 1925. Serial No. 49,101.

To all whom it may concern:

Be it known that I, VAUGHAN L. ANDREW, a citizen of the United States, residing at Superior, in the county of Douglas and State 5 of Wisconsin, have invented certain new and useful Improvements in Windmills, of which the following is a specification, reference being had therein to the accompanying drawing.

10 This invention relates to windmills and has special reference to a novel oiling system therefor.

The principal object of my present invention is to provide a more efficient and practical oiling means than heretofore employed, and another object is that of simplicity and 15 inexpensiveness of parts.

Still other objects and advantages of the novel construction will appear in the further description of the invention.

20 Referring now to the accompanying drawing, forming part of this application, and in which like reference characters indicate like parts:

25 Figure 1 is a top plan view of a rocker arm in a windmill head equipped with my improved oiling device;

Figure 2 is a side elevation of Figure 1 showing a portion of the exterior of the oil 30 carrying bowl of the head, and

Figure 3 is a transverse section on the line 3—3, Figure 1.

1 represents the housing or bowl of the windmill head, upon one side of which the 35 rocker arm 2 is pivotally supported as at 3, and the opposite or free end is attached to the pump plunger rod 4 as by the ball and socket joint indicated at 5. The internal gear illustrated at 6 is common to such form 40 of windmill heads, and is rotated by the windmill shaft 7 which is provided with a suitable laterally extending bearing from the side of the bowl 1. A pitman indicated at 8 connects the rocking arm 2 with the internal gear 6, the free end of said arm being 45 reciprocated by the rotary motion of the gear, and the arm in its cycle of travel is raised and lowered vertically past the uppermost circumferential edge of the gear, and when there is oil in the bowl it is obvious that the same will be carried around both internally and externally on the internal gear 6.

50 Upon the side of the arm 2 next to the gear 6 is formed a laterally projecting web comprising the portions 9 and 10, that in-

dicated at 9 having a groove or channel 11 formed therein next to the central body portion of the arm and this groove extends from the oil hole 12 in the hub 13 of the pin 14 60 at one end to the oil hole 15 in the hub 16 at the pivotally mounted end of the arm, so that any oil collected in this groove will, as it is swashed from one end of the groove to the other, supply oil to both of said holes. 65 Adjacent the oil hole 12 and offset slightly from the groove 11 is a cup-shaped recess 17, having a vertical hole 18 therein for the dripping of oil downwardly upon the lower connection of the pitman 8, the bottom of 70 the recess 17 being slightly higher than the bottom of the channel 11.

The portion 10 of the laterally projecting web is stepped downwardly slightly and the upper face of said web is comparatively flat 75 though inclined slightly downwardly and outwardly from the body portion of the arm, there being an oil hole 19 at the forward extremity of said upper surface of the web into the ball bearing 5, so that some 80 oil will be carried along in the corner between the body portion of the arm and the web and fed to the ball bearing, but as is well known to those versed in the art, the necessity of such oiling of the ball bearing 85 is comparatively slight in respect to other parts of the windmill mechanism and that an over oiling of this joint is not desirable, thus the provision for caring for an excess of oil in that it will run off laterally from 90 the surface of the web 10.

Intermediate of the upper extremity of the internal gear and the pivotal point 3 of the arm 2 and transverse the latter is 95 mounted the oil scraping dipper 20, it having formed integral therewith the hooked finger 21 which forms the pivotal connection of the dipper with the body portion of the arm 2, the hole in said arm being such that the dipper may be hooked or unhooked from engagement with the arm, and the inner extremity of the finger 21 rests within the jaw like bearing 22 formed upon the upper portion of the outer edge wall 23 of the channel 11, thus forming a substantial 100 and wide bearing for the pivotal member of the dipper 20. This dipper is substantially flat though it has a slightly dished upper surface as indicated at 24, there being a surrounding wall on practically two and one-half sides thereof as indicated at 25 and 26. 105 A web or rib 27 is formed on the under side

of the dipper which leads inwardly over the arcuately shaped notch 28 formed in the upper face of the outer edge wall 23 of the channel 11 so that in the event of the oil supply being low or the rotation of the mill being slow, oil adhering to the under side of the dipper will traverse same inwardly and downwardly into the channel 11 so as to insure an adequate supply of oil from the internal gear to the channel irrespective of change in conditions or circumstances as long as there is any oil whatever available in the windmill head.

It is apparent from the above that as the arm 2 is reciprocated upwardly and downwardly past the rotating gear 6 the same travelling in normally a clockwise direction as viewed from Figure 2 of the drawing, and carrying oil, the dipper 20 will intermittently rest upon the upper circumferential face of the gear during which time oil will be scraped therefrom either into the dipper or carried by the under side thereof, thence to the channel 11, so that as the arm continues its travel up and down the oil within the channel will be swashed from end to end thereof thus adequately oiling all of the journal portions heretofore described.

Having thus described my invention, what I claim and desire to secure by Letters Patent, is:

1. In combination, a windmill head including an oil bowl, a rocker arm pivotally mounted above said bowl having journal bearings operably associated therewith, an internal gear wheel within the bowl cooperatively connected with the rocking arm, an oil channel longitudinally of the arm and upon one side thereof, an oil scraping dipper pivotally carried by the arm and inter-

mittently engaging the outer surface of the gear wheel for conveying oil therefrom into the channel and thence to the journal bearings of the arm.

2. In a windmill the combination with an oil bowl in the head thereof, a rocker arm pivotally supported at one end and connected to a reciprocable rod at the other end, and a rotatable internal gear within said head for imparting motion to the rocker arm, of an oil channel longitudinally of the rocker arm and at one side thereof, and a scraping dipper pivotally carried above the oil channel and intermittently contacting the upper smooth surface of the gear wheel whereby oil is conveyed from the gear wheel into the channel and thence to the pivotal connection of the arm.

3. In a windmill lubricator, a rocker arm and bearing surfaces associated therewith, an internal gear wheel adapted to carry lubricant on the outer surface thereof, an oil conveying trough longitudinally of one side of the rocker arm, a scraping dipper pivotally carried by the rocker arm above said trough and intermittently engageable with the gear wheel, substantially as and for the purpose described.

4. In a windmill lubricator, a lubricant bowl, a rocker arm having a bearing associated therewith mounted above said bowl, a rotating oil carrying member within said bowl, a scraping dipper pivotally mounted upon the arm intermediate of its ends and intermittently engageable with said rotating member, and means for conveying oil from said dipper to the bearings associated with said arm.

In testimony whereof I hereunto affix my signature.

VAUGHAN L. ANDREW.
